ADVERTISING DEVICE

Filed Dec. 13, 1930

UNITED STATES PATENT OFFICE

JOHN STONE STONE AND GORDON WILSON, OF SAN DIEGO, CALIFORNIA

ADVERTISING DEVICE

Application filed December 13, 1930. Serial No. 502,016.

This invention relates in general to advertising devices.

One of the objects of this invention is to provide an advertising device belonging to that class in which the attention of the public is attracted by an unexpected motion and in which its attention is held by an expectation of a repetition of the motion.

A further object of this invention is the provision of mechanism in connection with a display device such as a bust or picture of a man or woman on the bill board or other display surface associated so that clouds of smoke or a compound simulating smoke issue from the mouth of the bust or picture to indicate the act of smoking.

A further object of this invention is the provision of mechanism of this type arranged so that the smoke is caused to issue periodically in puffs at reasonable intervals from the mouth of the bust or picture.

A further object of this invention contemplates mechanism employing chemicals which are properly mixed and caused to issue in puffs periodically to simulate tobacco smoke.

These and many other objects as will appear in the following disclosure are successfully attained by means of this invention.

This invention resides substantially in the combination, construction, arrangement and relative location of parts, all as will be set forth in details below.

Referring to the drawings:

Figure 1 is an elevational view with some parts in cross-section and some parts broken away of the apparatus comprising this invention;

Fig. 2 is an illustration of a bust of advertising device or display with the smoke discharge arranged so that the smoke will issue from the mouth of the bust;

Fig. 3 is an illustration of a picture display of a man on a display surface or advertising board with the smoke discharge associated therewith so that the smoke issues from the mouth of the pictorial representation.

The prime object of this invention is the provision of a simple mechanism for use in

conjunction with advertising display especially in connection with the advertising of smoking paraphernalia such as cigarettes, cigars, smoking tobacco, pipes and the like.

It is, of course, apparent that the principles of this invention and the construction involved may be applied to any form of advertising device in which intermittent puffs of smoke would be used to attract attention.

The invention may be said generally to relate to that class of advertising devices in which the attention of the public is attracted by an unexpected motion and in which its attention is held by an expectation of a repetition of the motion. The invention is, of course, adapted to make forms of advertising and has only been shown in connection with bust and pictorial representations for purposes of illustration.

The term "smoke" is used in this specification to designate visible vapors, smoke or fog resembling tobacco smoke and in order for the "smoke" to have such an appearance, the mean diameter of its particles should not too greatly depart from 2.5×10^{-5} cm., which is the mean diameter of the particles of tobacco smoked. The vapor of ammonium chloride (NH_4Cl) or sal ammoniac has particles whose mean diameter is 10^{-5} cm. and is therefore indistinguishable from tobacco smoke, but fogs or mists, the mean diameter of whose particles are of the order of 10^{-4} cm., have still sufficient resemblance to tobacco smoke to be used for the purposes of this invention. This invention proposes to make use of both of these "smokes" or "aerosols".

When a fog or mist is used, they are generated by producing puffs of the vapor of some of the tetrachlorides, such as TiCl_4 , SnCl_4 , SiCl_4 or other extremely hygroscopic substances such as SO_3 . These vapors, because of their pronounced hygroscopic properties, attract moisture from the air and produce a fog or mist. These vapors may be accompanied by a certain proportion of ammonia (NH_3) vapor which neutralizes the acid odor of the vapor. Water vapor in the form of hygroscopically saturated air, may also be added simultaneously to the

100

puff in order to supply a full quota of water for precipitation by the tetrachloride vapors.

In the most approved form of this invention in producing a vapor which cannot be distinguished from cigarette smoke HCl and NH₃ vapors are simultaneously ejected in each puff to produce a cloud of NH₄Cl vapor. The particular embodiment of the invention as disclosed in the drawings will be described in connection with these chemicals although it will be understood that the other chemicals disclosed and their equivalents are to be considered within the scope of this invention.

Reference will not be made in detail to the drawings.

At 1 is an inlet pipe leading into a small container 2, through which air is passed for drying it. This container will have in it some hygroscopic compound such as calcium chloride which rapidly and efficiently removes all moisture from the incoming air. A delivery pipe 3, having a check valve 4 in it, connects the container with the cylinder 5. Within the cylinder is a piston 7' mounted on a piston rod 7 which passes through the stuffing box 6 at the lower end of the cylinder.

The piston rod extends to the other end of the cylinder and passes through an open spider 8 for guiding the movement thereof. At 13 is a discharge pipe from the cylinder having a check valve 14 therein. Check valves 4 and 14 are of the simple type and arranged so that when piston 7' is moving upwardly, check valve 4 is open permitting the delivery of air into the cylinder while check valve 14 is closed. On the downward stroke of the piston, check valve 4 is closed and check valve 14 opens.

The end of delivery pipe 13 is closed by means of a cork or rubber stopper 15 through which the small pipes or glass tubes 16 extend. The free ends of these pipes extend through the stoppers 19 and 20 in the glass receptacles 17 and 18 as shown. At 22 and 28 are containers similar to container 2 for holding a hygroscopic material for removing moisture from the air received in these containers through the inlets 21 and 27. Pipes 23 and 29 deliver from these containers into the glass containers 25 and 31 through the stoppers 24 and 30 as shown. Pipe 26 extends from near the bottom of container 25 through stopper 24 and through stopper 19 into container 17. Likewise pipe 32 extends from near the bottom of container 31 through stopper 30 and stopper 20 into container 18. Pipes 33 and 34 extend from near the top of containers 17 and 18 respectively through their stoppers and convey the two gases through the mouth or other discharge orifice to the atmosphere where, on mixing, the desired "smoke" is produced.

In connection with the bust form of display device the mechanism may be contained within the hollow body thereof with the discharges adjacent the mouth of the bust which may hold either a pipe, cigar or cigarette. This is illustrated in Fig. 2. In Fig. 3 is illustrated another form of display device representing a sign-board or bill-board having a pictorial representation of a person thereon smoking a pipe. The discharges 33 and 34 in this case are mounted on back of the board and arranged so as to blow smoke through the mouth of the pictorial representation. In this arrangement the mechanism may be contained in a box on the back of the board.

The lower end of piston rod 7 is provided with a cam follower in the form of a roller or groove pulley 9 which contacts with the edge of a cam 10. This cam 10 is connected to a shaft 12 which is driven through a suitable reducing gear by means of the motor 11. Any form of driving device and gear train may be employed for driving the cam, the only requirement being that the cam be driven at such a rate of speed that the puffs of smoke will issue at the desired intervals. In practice a speed of rotation of from eight to fifteen revolutions per minute of the cam best simulates the act of smoking. Pipes or glass tubing 21, 23, 27, 29, 26 and 32 have capillary bores of a size depending upon the number of puffs and the volume of the same that are required per minute. The capillary diameter of these tubes should ordinarily be sufficient to allow the syphoning of approximately two to three drops of liquid per minute from containers 25 and 31 to containers 17 and 18.

In one embodiment of the invention ammonium hydrate is placed in container 23 and hydrochloride acid is placed in container 31. In container 17 is placed unslaked lime and in container 18 is placed sulphuric acid. The size of containers 25, 31, 17 and 18 merely depends upon the frequency with which fresh materials may be conveniently added.

In the operation of the device the motor is started which through agency of cam 10, cam follower 9 and piston rod 7 causes the movement of piston 7' at the proper intervals in cylinder 5. The cam as shown if moved in a clockwise direction will gradually cause the piston 7' to move upwardly until cam follower 9 slips off the point thereof. The piston and its connected parts are then free to fall vertically under the action of gravity. On the upstroke of the piston, air is drawn into the cylinder through pipe 1, container 2, pipe 3 and valve 4. The moisture therein is removed during its passage through the hygroscopic material in container 2. When the piston 7' falls the air in the cylinder is forced through pipe 130

13 and valve 14, through pipes 16 and into containers 17 and 18. The ammonium hydrate is siphoned drop by drop from container 25 through pipe 26 into container 17. It reacts with the unslaked lime producing ammonia which fills all the free upper space in container 17. Likewise hydrochloric acid is siphoned from container 31 drop by drop through pipe 32 into container 18. Due to its greater affinity for water the sulphuric acid in container 18 absorbs the water from hydrochloric acid falling therein resulting in the collection of hydrochloric acid gas in the top container 18.

15 As the piston 7' falls downwardly, air is forced into containers 17 and 18 creating a pressure therein and forcing an amount of ammonia gas and hydrochloric acid gas through pipes 33 and 34, depending upon the volume of cylinder 5. The intermixing of the ammonia gas and hydrochloric acid gas in the atmosphere results in the formation of ammonium chloride which, issuing in puffs from pipes 33 and 34, closely resembles tobacco smoke. The frequency and volume of the puff of smoke depend upon the frequency of movement of piston 7' and the volume of cylinder 5 and the diameter of the capillary bores in pipes 26 and 32.

25 30 As the reagents gradually siphon from containers 25 and 31, the space left by their removal is taken up by dry air which flows thereinto through pipe 21, container 22 and pipe 23 and pipe 27, container 28 and pipe 29 respectively. As already pointed out, containers 22 and 28 contain any suitable material for drying the air as it passes therethrough.

It is pointed out that the resulting ammonium chloride fumes are in no way injurious to humans, being if anything, rather beneficial even though blown into a comparatively small shop or room.

From the foregoing disclosure it will be apparent that we have embodied certain principles of construction and operation in one physical form of apparatus for purposes of illustration and it will likewise be apparent that these principles may be embodied in other physical apparatus without departing from the spirit and scope of this invention.

We do not further desire to be strictly limited by the disclosure as given in an illustrative sense but rather to the field of invention as defined in the appended claims.

What we seek to secure by United States Letters Patent is:

60 1. In an apparatus of the type described, the combination with a display device, of means for generating gases which when mixed produce a cloud of dense smoke, discharge means connected to said means and means also connected to said first means for

causing the gases formed to issue from said discharge means.

2. In an apparatus of the type described, the combination comprising two containers, two receptacles connected to said containers by means for delivering the contents of the containers to the receptacles in small drops, means for delivering pulsations of air to said receptacles and means including juxtaposed discharge nozzles connected to said receptacles, the air pulsations effecting gas discharge from the nozzles.

3. In an apparatus of the type described, the combination comprising two containers, two receptacles connected to said containers through capillary pipes, means for delivering a predetermined volume of air to said receptacles at desired intervals and juxtaposed discharge nozzles connected to said receptacles, through which gases generated in the receptacles issue in puffs.

4. In an apparatus of the type described, the combination comprising interconnected means for forming ammonia gas and hydrochloric acid gas, juxtaposed discharge nozzles connected to said means so that the two gases are delivered therefrom, and means for supplying dry air at predetermined intervals in a predetermined volume to said means.

5. In an apparatus of the type described, the combination comprising a container for ammonium hydrate, a container for hydrochloric acid, two receptacles, pipes having capillary bores connecting one container with one of the receptacles and the other container with the other of the receptacles, means for supplying air at predetermined intervals to both of said receptacles and juxtaposed discharge nozzles connected to said receptacles in which the gases from the receptacles are expelled therefrom and permitted to combine from which resulting compound is discharged, the receptacle connected to the container for ammonium hydrate containing unslaked lime and said receptacle connected to the container for hydrochloric acid containing sulphuric acid.

6. In an advertising device of the type described, the combination with a display device simulating a human being smoking, of means for forming ammonia gas and hydrochloric acid gas, and means for intermittently supplying air to said first means to force predetermined quantities of the ammonia gas and the hydrochloric acid gas into the atmosphere so that the discharge and combining of the gases is associated with the mouth of the human being whereby puffs of vapor simulating smoke are caused to issue therefrom.

7. In an apparatus of the type described, the combination with a display device simulating a human being smoking, of means for forming two gases which when reaching the

atmosphere mix and react to form vapor simulating smoke, a discharge device connected to said means and associated with the display device adjacent the mouth portion thereof and means connected to said first means for delivering air at predetermined intervals thereto to force the gases to the discharge device where they mix to form a vapor compound simulating smoke which issues from the mouth of the display device.

8. In a display device of the type described, the combination with means simulating a human being smoking, of two sets of containers for holding chemicals, the containers of each set being connected together, a gas discharge pipe for one container of each set connected thereto, the ends of the two gas discharge pipes terminating adjacent the mouth of the simulated human being, and means for simultaneously effecting the delivery of a chemical from one container of each set to the other container of each set to effect the generation of different gases and discharging those gases through the discharge pipes into the atmosphere at intervals from the mouth of the simulating human being to produce puffs of dense smoke.

In testimony whereof we have hereunto set our hands on this 6th day of December A. D., 1980.

JOHN STONE STONE.
GORDON WILSON.
